ENVELOPE

Samuel Schwartz, Cleveland, Ohio

Application December 6, 1932, Serial No. 645,902

3 Claims. (Cl. 229—74)

This invention relates to an envelope having a hole through it whereby it may be hung on a suitable object. The specific purpose of the invention is to provide such a device so constructed that the portion of the envelope containing a document may be completely sealed to retain such document in place, with its message effectively hidden from view, and in which the attaching opening through the envelope is of such shape 10 that when the envelope is passed over the neck of a milk bottle of appropriate size the envelope will be retained against dislodgment by wind. Thus my envelope is especially adapted for the delivery of a bill with the bottle of milk.

15 The attaching hole through the envelope is made adjacent one end and is of an elliptical form, preferably with the major axis transverse of the envelope. The size of the opening is such with reference to a standard milk bottle that by 20 bending the paper of the envelope the hole, which is thus caused to assume in effect a circular form, may be passed over the bead at the top of the bottle neck, and will thereafter hug the neck below the bead, thereby effectively anchoring the envelope to the bottle, preventing its being lost or 25 blown away.

The compartment of the envelope which may receive the milk bill is closed from the anchoring hole by a transverse glued region which effectively separates the envelope into two compartments, of which the major one may be designated as the message compartment, and the minor one the attaching compartment. The glued flap of the envelope serves to seal the message within 35 its compartment, and may reinforce the attaching compartment. The message compartment is preferably of the outlook form, having either an opening or a transparent portion at the front.

When such an envelope as described is used for 40 the delivery of the milk bill, the bill is placed in the message compartment, is folded so that only the address shows through the outlook window. The flap is then sealed so that the bill is effectively and secretly retained within the compartment. Then by bending the attaching portion 45 of the envelope so that the opening assumes an approximately circular form, such end of the envelope is effectively passed over the bead of the bottle and the envelope thus becomes anchored 50 to the bottle.

My invention is illustrated in the drawing hereof and is hereinafter more fully explained, and the essential novel features are summarized in the claims.

55 In the drawing, Fig. 1 is a perspective of my

envelope in place on a milk bottle; Fig. 2 is a plan of the envelope in unattached form; Fig. 3 is an enlarged longitudinal section of the envelope taken on the plane indicated by the offset line 3—3 on Fig. 2 and indicating a suitable document, (for clearness, a card of single thickness) within the envelope; Fig. 4 is a plan of the blank for the envelope before the same is folded; Fig. 5 is a view of an envelope openable at the end and embodying my invention.

As shown in Figs. 1, 2 and 3, the entire envelope A is divided into two compartments B and C by a transverse region D, caused by gluing the face a of the envelope to the back a' thereof. The compartment B is the anchoring compartment 70 and contains the opening b, which, as shown, is of elliptical character with the major axis transverse of the envelope. This opening extends through both the front of the envelope and the back thereof, the back portion, as shown by the blank in Fig. 4, being made partly by the main back flap a' and partly by the end flap a², which overlap each other and are glued together.

The message compartment C preferably has the outlook opening c, which may have a strip 80 of glassine or other transparent material extending across the opening and secured on the inside of the envelope front, as indicated in Fig. 4.

If a blank of the form shown in Fig. 4 has glue on the region D and also at the edges of the flap a', as shown at a³, then when folded the two end flaps a² and a⁴ are first turned in and the side flap a' folded over them and glued to the end flaps by the glued portions a³ and both the side flap a' and the end flap a² are glued to the envelope front a 90 by the glued region D. This produces the envelope of the form shown in Fig. 2. Now after the bill E or other message is inserted in the message compartment C, the closing flap a⁵ of the envelope is folded over and glued down to the side flap a' and 95 to the two end flaps a² and a⁴ by the ordinary glued region a⁶ which the user moistens for the purpose.

It will be seen that when the bill or other matter is placed in the message compartment with the address opposite the outlook window and the flap a⁵ sealed closed, the bill is effectively enclosed and its data hidden from view. Also, the opening of the anchoring compartment, which extends 100 through the front and portions of the side flap and one end flap, is further reinforced by the glued down main flap a⁵. Accordingly, this attaching region is well reinforced and in use may be readily passed over the bead f of a milk bottle 110

F, as shown in Fig. 1, without danger of tearing the envelope.

The minor axis of the elliptical opening is less than the diameter of the bottle neck, while the major axis is greater than the diameter of the bottle neck. It results from this that when the envelope is in place there is necessarily a pulling of the material longitudinally of the envelope to warp the surface of the envelope and make the opening through such warped surface in effect substantially circular. Thus, when in place, the envelope closely hugs the neck of the bottle and its tendency to resume a flat form maintains a snug engagement with the neck. Accordingly, while the envelope may be easily slipped into place on the bottle neck over the bead of the bottle, it effectively holds its position and cannot blow away or become lost.

In Fig. 5 I have illustrated my invention as applied to an open end envelope E. This envelope is formed by folding the material from which it is to be made back on itself as at e' then folding the opposite side e² into an overlapping position relative to the side e' and securing these sides together with a suitable adhesive to form one face e of the envelope. Both ends of the envelope E are provided with flaps e³ and e⁴ respectively, the flap e³ being folded over overlapping and secured to the sides e' and e². The flap e⁴ is provided with dry adhesive e⁵ so that it may be folded over and sealed after the bill or other matter has been inserted in the envelope.

In envelopes of the type shown in Fig. 5, the adhesive at the transverse region which divides the envelope into two compartments serves an important purpose. When the invoice or other matter is inserted in the envelope through the open end e⁶ it is prevented from obstructing the elliptical opening b by the region D which in this instance is interposed between the open side of the envelope and the elliptical opening.

It will be seen that I have provided a simple means for effectively attaching a milk bill to a milk bottle without disclosing the data on the bill. Postage and other expense of mailing is avoided, and the bill is automatically brought to the attention of the recipient of the goods. My

envelope may be cheaply constructed, and experience has demonstrated that it is very satisfactory in use.

I claim:

1. An envelope comprising a rectangular front portion, a main flap and a pair of end flaps at the back, said flaps being secured together to form a pocket having its end edges and one longitudinal edge closed and the other longitudinal edge open, said front portion and at least one of said flaps having transversely elongated openings therethrough registering with each other, there being a region adjacent the openings where the front portion is secured to the last mentioned flap and the main flap to form two compartments within said pocket, one of said compartments having said transversely elongated opening clear through it and the other compartment having a longitudinally elongated sight opening through its front. 80

2. An envelope comprising a substantially rectangular front portion, flaps adapted to form the back of said envelope, an additional openable flap providing access to the interior of said envelope, said front portion and at least one of said flaps having elongated openings therethrough registering with each other, there being a region adjacent the openings where the front portion is secured to the back portion to form two compartments within said envelope, one of said compartments having therethrough said aforementioned 95 elongated openings, and the other compartment having a longitudinally elongated sight opening through its front. 100

3. An envelope comprising a substantially rectangular front portion, flaps adapted to form the back of said envelope, an additional openable flap providing access to the interior of said envelope, said front portion and at least one of said flaps having elongated openings therethrough registering with each other, there being a region adjacent the openings where the front portion is secured to the back portion to form two compartments within said envelope, one of said compartments having therethrough said aforementioned 110 elongated openings. 115
